UNITED STATES PATENT OFFICE.

CARROLL POTTER, OF PHILADELPHIA, PENNSYLVANIA.

APPARATUS FOR CASTING LEAD.

SPECIFICATION forming part of Letters Patent No. 694,418, dated March 4, 1902.

Application filed September 18, 1900. Serial No. 30,380. (No model.)

To all whom it may concern:

Be it known that I, CARROLL POTTER, a citizen of the United States, residing at the city of Philadelphia, in the county of Philadelphia and State of Pennsylvania, have invented certain new and useful Improvements in Apparatus for Casting Lead, of which the following is a specification.

The present invention constitutes an improvement applicable to the apparatus described and claimed in Letters Patent No. 451,407, dated April 28th, 1891, and granted to Henry Herbert Lloyd; and its principal object is to provide safety devices and appliances whereby danger from the escape of molten lead is obviated and whereby the operation of the apparatus is hastened and made more reliable.

To these and other ends, hereinafter set forth, the invention comprises the improvements about to be described, and particularly pointed out in the claims.

The nature, characteristic features, and scope of the invention will be more fully understood from the following description, taken in connection with the accompanying drawings, forming part hereof and in which is illustrated, principally in elevation and in part in section, apparatus embodying features of the invention.

In the drawings the apparatus illustrated at the right-hand side consists of a pot or crucible *a* for containing molten lead, and of what may be termed a "pneumatic pump" *b* for forcing the lead from the pot into the mold *c*. This pneumatic pump is fully described in the patent referred to. However, I may say that lead enters it by way of the check-valve *d* and is forced from it by way of the nozzle *e*. The air is supplied from a reservoir *f* by way of a pipe *g*.

The mold *c* is a two-part mold, and its parts must be held together very firmly in order to resist the pressure of the incoming metal, which is fed into it under pressure, either by means of the pneumatic pump described or in any convenient way. In accordance with my invention the two parts of the mold are held together by means of a piston or plunger *h*, mounted to work in a suitable cylinder, which in turn is supported by a strong yoke attached to the bed-plate *i*, on which the mold

c is laid. This piston is forced down onto the mold against its spring *j* by means of air-pressure created in the cylinder—for example, 55 from the reservoir *f*. The area of the piston should equal or exceed the internal area of the mold in cases where the pump and the cylinder are both supplied with air at the same pressure, as shown in the drawings. The 60 cylinder is supplied with air by way of the pipe *k*, and both the pipes *g* and *k* may be supplied from the pipe *l*, that communicates with the air-reservoir *f*. *m* and *n* indicate valves, and, as shown, they are three-way valves. 65 The valve *m* serves to control the supply of compressed air to and from the piston and cylinder, and the valve *n* serves to control the supply of compressed air to and from the pump *b*. It will be noted that the valve *m* is 70 nearer to the reservoir *f* than the valve *n*. The purpose of this arrangement is to insure the clamping together of the parts of the mold by the piston before the pump *b* can be operated to feed molten lead, as will be herein- 75 after more fully described.

The mode of operation of apparatus embodying my invention may be described, in connection with the accompanying drawings, as follows, and in this connection it will be 80 assumed that the valves *m* and *n* are both turned so as to communicate with the exhaust-pipes or atmosphere and into position for interrupting the passage of air from the reservoir *f*: The two parts of a mold are 85 then closed together and the mold is slipped under the piston, which is held in elevated position by means of the spring *j*. The nozzle *e* is then connected with the mold. The valve *m* is then turned into the position 90 shown in the drawings, so that compressed air reaches the effective area of the piston and drives it downward, so that it clamps and holds the two parts of the mold firmly together. The valve *n* is then opened, so that 95 compressed air reaches the pump *b* and forces molten lead into the mold, of which the parts are firmly held together, as described. The action of the piston is very rapid and exceedingly reliable, and it is impossible to operate the pump until after the piston has 100 clamped the mold, because compressed air cannot reach the pump until after it has reached the piston, due to the positioning or

location of the valves in respect to the air-reservoir and the parts which they control. Should the valve *n* be operated first, air cannot reach the pump, because it cannot pass the valve *m*, and as soon as the valve *m* is turned so that air can pass it the air reaches the piston as soon as it can the pump.

It will be obvious to those skilled in the art to which the invention relates that modifications may be made in details without departing from the spirit thereof. Hence I do not limit myself to the precise construction and arrangement of parts hereinabove set forth, and illustrated in the drawings; but,

Having thus described the nature and objects of my invention, what I claim as new, and desire to secure by Letters Patent, is—

1. The combination of a supply of compressed air, a pneumatic pump, a piston and its cylinder for clamping molds, pipe connec-

tions from the air-supply to the cylinder, branch-pipe connections from the first-mentioned pipe connections to the pump, a three-way valve located on the supply side of the first-mentioned pipe connections, and a three-way valve located in the branch-pipe connections, substantially as described. 25

2. The combination of a pneumatic pump, a plunger and its cylinder for holding molds, a spring for lifting the plunger, the pipe for the pressure fluid, and pipe connections including valves and extending from said pipe to the pneumatic pump and to the cylinder, substantially as described. 30

In testimony whereof I have hereunto signed my name.

CARROLL POTTER.

In presence of—
W. J. JACKSON,
K. M. GILLIGAN.
